UNITED STATES PATENT OFFICE.

STEPHEN J. McNICHOL, OF SWAMPSOFT, MASSACHUSETTS, ASSIGNOR OF ONE-THIRD TO LYNN LAST COMPANY, OF LYNN, MASSACHUSETTS, A CORPORATION OF MASSACHUSETTS.

LATHE FOR TURNING LASTS.

1,179,125.

Specification of Letters Patent.

Patented Apr. 11, 1916.

Application filed June 1, 1915. Serial No. 32,011.

To all whom it may concern:

Be it known that I, STEPHEN J. McNICHOL, a citizen of the United States of America, and a resident of Swampscott, in the county of Essex and Commonwealth of Massachusetts, have invented certain new and useful Improvements in Lathes for Turning Lasts, of which the following is a specification.

- 10 The present invention relates to wood turning machines and particularly to machines of this character which are adapted to turn irregular shapes such as lasts to be used in the manufacture of boots and shoes.
- 15 The particular object of the invention is to provide means whereby deep hollows in the last on either side of the comb may be automatically turned on the machine, thus dispensing with the hand work which is usually performed in the manufacture of certain styles of lasts known to the trade as thin comb lasts.

Another object of the invention is to provide such a mechanism which may be readily applied to existing last turning lathes at little expense.

A further object of the invention is to provide a cutter head of small size with cutting knives in different planes with their cutting edges at different distances from the axis of said head whereby the work is successively cut by each of the knives during the rotation of said head.

Another object of the invention is the production of a cutter head particularly adapted for work of this character and in which the knives may be quickly removed for repair or sharpening but in which said knives will be securely held during the turning operation, provision being also made for the adjustment of the finishing knife.

The invention further consists in certain novel features of construction and arrangement of parts which will be fully understood by reference to the description of the drawings and to the claims hereinafter given.

Of the drawings: Figure 1 represents a front elevation of a shoe last turning machine embodying the principles of the present invention. Fig. 2 represents a plan of a portion of the machine showing the

traveling frame, the revoluble cutter and its driving mechanism, and the wheel adapted to coact with the model. Fig. 3 represents a section of the end of the revoluble shaft, its cutter head, and the bearing for the latter. Fig. 4 represents a transverse section of the same, the cutting plane being on line 4-4 on Fig. 3, and Fig. 5 represents a sectional detail of the opposite end of the cutter shaft.

Similar characters designate like parts throughout the several figures of the drawings.

The present invention is shown in connection with one well-known type of last turning lathe, but it will be understood that the invention may be attached to any of the well-known lathes.

The machine shown in Fig. 1 has side frames 10 to the upper end of which is pivoted a swinging frame 11, carrying means for holding a model 12 and also means 12^x for holding the work to be operated upon.

Suitable means are provided for rotating the model and work holding means but as all of these parts and the operation thereof are old, it is deemed unnecessary to give any detailed description herein.

The model 12 coacts with a pattern wheel 13 which differs from those in general use only in the fact that it is of smaller diameter. It is revolubly mounted on a slide 14 adapted to be adjusted toward and from the front of the machine in a guideway in a bracket 15 extending upwardly from a frame 16 mounted to reciprocate longitudinally of the machine on ways 17-17^x all in the usual manner.

In the rear of the work support or holding means 12^x is a small cutter head 18 secured to or formed upon the end of a revoluble shaft 19 mounted to revolve in bearings 20-21 secured to uprights 22-23 of the frame 24 adapted to reciprocate longitudinally of the machine on ways 17-25 in the usual manner.

When it is desired to apply the present invention to a machine of the usual construction, the usual frame 24 is divided and separating members 26 inserted between the ends 27 to give the frame 24 greater length than the frames on machines of this character.

now in general use. This lengthening of the frame 24 makes it possible to construct the shaft 19 of greater length than the longest block to be mounted on the work holding members 12^x and to rotate said shaft 19 directly by means of a pulley 28 secured to the end thereof opposite to that on which the cutter head 18 is secured.

The pulley 28 is driven by a belt 29 from 10 the usual revoluble drum 30 found on all machines of this character. The shaft 19 is inclined relatively to the front of the machine with the pulley 28 further to the rear than the cutter head 18, thereby providing 15 sufficient space to permit the rotation of the work without the latter conflicting with said shaft during the last turning operation.

The end of the shaft opposite the pulley 28 is provided with an enlarged cone-shaped 20 end 31, the outer face of which has a radial recess 32 therein. In the bearing 21 is mounted a revoluble member 33 having an enlarged end 34 abutting the inner face of the bearing 21. The inner face of this enlarged end 34 is provided with a radial recess 35. Interposed between the opposed 25 faces of the member 31 and the flanged head 34 is an intermediate member 36 having radial recesses 37 and 38 in opposite faces thereof, these recesses being perpendicular 30 to each other. The recesses 32, 37, 38 and 35 are disposed at right angles to each other and prevented from movement relative to each other by means of a pin 39 disposed in 35 the intermediate member 36 with its ends projecting into the cone-shaped end of the shaft 19 and the flanged head 34 as indicated in dotted lines in Fig. 3 of the drawings.

40 Disposed in the recess 32 is a cutting knife 40 and similarly disposed in the recess 37 is a cutting knife 41. In the recess 38 is positioned the cutting knife 42, while in the recess 35 is positioned the finishing cutter 43. 45 It is apparent from an inspection of Fig. 3 of the drawings that these cutting knives 40, 41, 42 and 43 are all in different vertical planes.

By an inspection of Fig. 4 of the drawings 50 it will be noted that the cutting edge of the knife 41 is farther removed from the axis of the shaft 19 than the cutting edge of the knife 40 and the cutting edge of the knife 42 is farther removed from said axis than the 55 cutting edge of the knife 41, while the cutting edge of the finishing knife 43 extends still farther outwardly. By means of this construction as the cutting head 18 rotates in the direction of the arrow α on Fig. 4 of the drawings the cutting knives 40, 41, 42, and 43 will successively act upon the work in different planes, the material in any one portion of the work being removed in four sections, a portion of the material first being 60 cut away by the knife 40 and then other

portions being successively cut away by the knives 41, 42, and 43.

The knife 43 is the finishing knife and has a greater amount of cutting edge as indicated at 44 in Figs. 2, 3, and 4 of the drawings. Each of the knives 40, 41, and 42 is provided at its inner end with a cylindrical hole through which extends a clamping bolt 45 threaded to the cone-shaped end of the shaft 19 as indicated at 46. By 70 means of this bolt 45, the flanged head 34, the intermediate member 36, and the enlarged cone-shaped end of the shaft 19 are drawn together and the knives positioned in the various recesses of these members are 75 securely clamped in position. As the openings in the knives 40, 41, and 42 are cylindrical and fit the bolt 45, it is obvious that there cannot be any end movement of these knives while on account of the clamping of the 80 knives by means of the bolt 45 there can be no lateral movement of these knives and all chattering is prevented. The opening in the inner end of the finishing knife 43 is elongated as shown at 47 in Fig. 4 of the drawings and threaded to the rear end of the knife 43 is a screw 48 having a head 49 extending into a groove 50 in the inner face of the flanged head 34, thereby preventing 85 end movement of said screw as it is turned 90 about its axis.

It is obvious that by turning the screw the knife 43 may be adjusted endwise in either direction. The larger end 44 of the finishing knife 43 overbalances the smaller ends of 100 the other cutting knives and to obviate this difficulty a ring 51 is secured to the periphery of the flanged member 34 by means of a screw 52 or similar securing member. This ring 51 is eccentric as shown in Fig. 4 with 105 the greater thickness disposed opposite to the end 44 of the finishing knife 43. The ring 51 also varies in width as shown in Fig. 2 of the drawings, this variation in width 110 being for the purpose of equally balancing the weight of the knives extending beyond the periphery of the cutter head 18 so that in the rotation of the shaft 19 the entire cutter head will be perfectly balanced. The shaft 19 at one end is provided with the annular groove 53 into which extends a plate 115 54 secured to the end of the bearing 20 as indicated in Figs. 2 and 5 of the drawings.

The ring 51 is provided with an opening 55 therein opposite the screw 48 through 120 which a screw driver may be inserted to turn the screw 48 and adjust the knife 43 as desired. By means of this construction a cutter head of greatly reduced diameter may be used and thereby turn lasts with thin 125 combs, the hollowing out on opposite sides of the comb being entirely accomplished by means of a machine and dispensing with hand labor.

It is believed that the operation and many 130

advantages of this invention will be fully understood from the foregoing description.

Having thus described my invention, I claim:

- 5 1. In a machine of the class described, the combination with a work support and a model support, of a traveling frame; a revoluble shaft supported in a bearing thereon; a flanged member revolubly mounted in
10 a bearing on said frame; a bolt extending through said flanged member and threaded in the end of said shaft; cutting knives carried by said shaft and flanged member having openings in their inner ends through
15 which said bolt extends; and a wheel for engaging the model.

2. In a machine of the class described, the combination with a work support and a model support, of a traveling frame; a revoluble shaft supported in a bearing thereon; a flanged member revolubly mounted in
20 a bearing on said frame; a bolt extending through said flanged member and threaded in the end of said shaft; cutting knives carried by said shaft and flanged member having cylindrical openings in their inner ends through
25 which said bolt extends, said bolt being the same diameter as said openings; and a wheel for engaging the model.

3. In a machine of the class described, the combination with a work support and a model support, of a traveling frame; a revoluble shaft supported in a bearing thereon; a flanged member revolubly mounted in
30 a bearing on said frame; a bolt extending through said flanged member and threaded in the end of said shaft; an intermediate member on said bolt between said flanged member and shaft; cutting knives carried
35 by said shaft, intermediate member, and flanged member and having openings in their inner ends through which said bolt extends; and a wheel for engaging the model.

4. In a machine of the class described, the combination with a work support and a model support, of a traveling frame; a revoluble shaft supported in a bearing thereon and having a radial recess in the end thereof; a flanged member revolubly mounted
45 in a bearing on said frame having a radial recess in the inner face thereof; an intermediate member between said flanged member and shaft having radial recesses in the opposite faces thereof; cutting knives positioned in said recesses and having openings in their inner ends; a clamping bolt extending through said flanged and intermediate members and said knives and threaded in the end of said shaft; and a
50 wheel for engaging the model.

5. In a machine of the class described, the combination with a work support and a model support, of a traveling frame; a revoluble shaft supported in a bearing thereon and having a radial recess in the end

thereof; a flanged member revolvably mounted in a bearing on said frame having a radial recess in the inner face thereof; an intermediate member between said flanged member and shaft having radial recesses in the opposite faces thereof; cutting knives positioned in said recesses and having openings in their inner ends; a clamping bolt extending through said flanged and intermediate members and said knives and threaded in the end of said shaft; means preventing the rotation of said intermediate and flanged members independently of said shaft; and a wheel for engaging the model.

6. In a machine of the class described, the combination with a work support and a model support, of a traveling frame; a revoluble shaft supported in a bearing thereon and having a radial recess in the end thereof; a flanged member revolvably mounted in a bearing on said frame having a radial recess in the inner face thereof; an intermediate member between said flanged member and shaft having radial recesses in the opposite faces thereof; cutting knives positioned in said recesses and having openings in their inner ends; a clamping bolt extending through said flanged and intermediate members and said knives and threaded in the end of said shaft; a pin embedded in said intermediate member and extending into said shaft and flanged member; and a wheel for engaging the model.

7. In a machine of the class described, the combination with a work support and a model support, of a traveling frame; a revoluble shaft supported in a bearing thereon and having a radial recess in the end thereof; a flanged member revolubly mounted in a bearing on said frame having a radial recess in the inner face thereof; an intermediate member between said flanged member and shaft having radial recesses in the opposite faces thereof; cutting knives positioned in said recesses and having openings in their inner ends; a clamping bolt extending through said flanged and intermediate members and said knives and threaded in the end of said shaft; means for adjusting one of said knives endwise; and a wheel for engaging the model. 100

8. In a machine of the class described, the combination with a work support and a model support of a traveling frame; a revoluble shaft supported in a bearing thereon and having a radial recess in the end thereof; a flanged member revolvably mounted in a bearing on said frame having a radial recess in the inner face thereof; an intermediate member between said flanged member and shaft having radial recesses in the opposite faces thereof; cutting knives positioned in said recesses and having openings in their inner ends; a clamping bolt 130

extending through said flanged and intermediate members and said knives and threaded in the end of said shaft; means for preventing endwise movement of said 5 revoluble shaft in its bearing; and a wheel for engaging the model.

Signed by me at Boston, Mass., this 25th day of May, 1915.

STEPHEN J. McNICHOL.
